Attorney

UNITED STATES PATENT OFFICE.

JOHN DIERKS, OF SAN FRANCISCO, CALIFORNIA.

STUDENT'S DESK.

1,301,406.

Specification of Letters Patent. Patented Apr. 22, 1919.

Application filed August 7, 1916. Serial No. 113,588.

To all whom it may concern:

Be it known that I, JOHN DIERKS, a citizen of the United States, residing in the city and county of San Francisco and State of California, have invented certain new and useful Improvements in Students' Desks, of which the following is a specification.

My invention relates to a student's desk to be used on any kind of stand or table, and the main portion is adapted to move side-wise in either direction and forward and backward so that several books may be read one after the other placed side by side or one above the other on the desk, and the objects of my invention are: first, to provide a desk of this class which is easily moved from side to side; second, to provide a desk of this class which is easily moved forwardly and backwardly; third, to provide a desk of this class which is provided with two differently inclined surfaces, the one for references and the other for books or both may be used for books as desired; fourth, to provide a desk of this class the book supports of which are adjustable; fifth, to provide a desk of this class with a novelly constructed book shelf in connection therewith so as to provide ready access of the books to the user, and sixth, to provide a desk of this class which is economical of construction, durable, easy of operation and will not readily deteriorate or get out of order.

With these and other objects in view as will appear hereinafter my invention consists of certain novel features of construction, combination and arrangement of parts as will be hereinafter described in detail and particularly set forth in the appended claims, reference being had to the accompanying drawings and to the characters of reference thereon which form a part of this specification, in which:

Figure 1 is a side elevational view of my desk complete, shown mounted on a fragmentary portion of a table which is shown by dotted lines. Fig. 2 is a front view of the same. Fig. 3 is a top view of the same with all above the shifting supports removed, and Fig. 4 a front elevational view of the book shelf showing books mounted thereon.

Similar characters of reference refer to similar parts throughout the several views.

The inclined book support 1, reference or book support 2, book support bars 3, support bars 4, adjusting bars 5, adjusting bars 6, handle bar 7, uprights 8, hinges 9, shifting

bars 10, hinges 11, shifting bars 12, hinges 13, upright supports 14, main support 15, book shelf support 16, extension bar 17 and binding bar 18 constitute the principal parts 60 of my desk.

The book support 1 is a flat piece provided with a small ledge 1^a along its lower edge for holding the books from sliding off of said lower edge. It is supported by means 65 of the bars 3 which are pivotally mounted at one of their ends on the uprights 8 at 3^a and at their other ends on the bars 4 at point 4^a these bars 3 and 4 are held in certain positions relatively to each other by means of 70 the adjusting bars 5, the one ends of which are pivotally mounted on the bars 3 at points 3^b and their other ends are provided with a plurality of holes adapted to engage with a plurality of holes in the lower ends of the 75 bars 4 so that the bars 4 may be positioned at different angles to the bars 3 by changing the bolt 5^a which connects the bars 5 with the lower ends of the bars 4. Mounted on these bars 4 is the reference or book support 2 80 which is provided on its lower edge with a small ledge 2^a for holding the books from sliding off of the said lower edge. It is provided near its top edge with a lamp 19 for lighting the desk. The bars 3 are supported 85 in certain position by means of the adjusting bars 6 which are pivotally mounted at one of their ends at point 6^a to the uprights 8, and they are provided with a plurality of holes in their other ends adapted to engage 90 with a plurality of holes in the lower extended ends of the bars 3 and be held in certain relative positions by means of bolts 6^b. Mounted on the lower extremities of these supports 3 and connecting the two together 95 is a handle bar 7 which is used for moving the movable portion of the desk to the different positions as desired. The uprights 8 are rigidly secured to the hinges 9 and the other members of the hinges 9 are secured to the 100 shifting bars 10. On the other ends of the bars 10 is secured one member of the hinges 11 and the other member of the hinges 11 is secured to the bars 12, the other ends of the bars 12 are secured to the hinges 105 13, the other members of said hinges being secured to the upright supports 14. Near the back side of the main support 15 is secured said uprights 14. This main support 15 is provided on its lower surface with a 110 plurality of cushions, preferably rubber, for preventing the scratching of the surface of

the table or desk upon which it is mounted. Secured to one of the supports 10 is an angle bar 16, one member of which extends outwardly on a horizontal plane and mounted 5 on this is an angled extension bar 17 and mounted between the two uprights of the two angle bars is another angle bar, the one member of which is adapted to extend through the upright member of the angle 10 bar 17 so that the angle bar 18 is adapted to be moved relatively to the angle bar 17 for changing the width of the space for the books as desired.

Though I have shown and described a 15 particular construction, combination and arrangement of parts I do not wish to be limited to this particular construction, combination and arrangement, but desire to include in the purview of my invention the construction, combination and arrangement substantially as set forth in the appended claims.

It is obvious that with this construction there is provided a student's desk which may 20 be readily shifted sidewise in either direction, the bars 10 and 12 hinge on the supports 14 and upright 8 as shown by dotted lines in Fig. 3, and gives the desk portion great flexibility sidewise, that by pushing on 25 the bar 7 backwardly the bars 10 and 12 will be moved inwardly as shown by dotted lines in Fig. 3, and the desk will be moved backward, that the adjusting bars 6 provide for changing the angle of the book support 1 as 30 desired and that the adjusting bars 5 provide for changing the angle of the book support 2 as desired, that the book shelf mounted on one of the bars 10 shifts with the shifting of the desk and is adjustable for different 35 quantities of books.

Having thus described my invention what I claim as new and desire to secure by Letters Patent, is:

1. In a student's desk, the combination of 40 an inclined book support, a pair of pivotally mounted inclined bars upon which said book

support is mounted, a secondary pair of bars pivotally mounted on said bars, means for adjusting the inclination of said secondary bars relatively to the first mentioned bars, a 50 book support secured to said secondary bars, a main support provided with a vertical side member, a plurality of horizontal bars hinged together and hinged to said vertical side member and means for adjustably supporting said first mentioned bars relatively to the horizontal bars. 55

2. In a student's desk, the combination of a main support provided with a vertical side member, a pair of hinged together members 60 pivotally connected to said vertical side member near each end, a supporting bar pivotally secured to the extended ends of said members connecting the extended ends of said members together, a pair of inclined 65 bars pivotally connected to said bar, means pivotally connected to the extended ends of said inclined bars and to said supporting bar for adjusting the angle of said bars and a book support mounted on said inclined bars. 70

3. In a student's desk, the combination of a main support provided with a vertical side member, a pair of hinged together members pivotally connected to said vertical side member near each end, a supporting bar pivotally secured to the extended ends of said members connecting the extended ends of said members together, a pair of inclined 75 bars pivotally connected to said bar, means pivotally connected to the extended ends of said inclined bars and to said supporting bar for adjusting the angle of said bars, a book support mounted on said inclined bars, a pair of secondary bars pivotally connected to the extended ends of said inclined bars, a shelf 80 secured thereto and means for adjusting the angle of said secondary bars to said inclined bars. 85

In testimony whereof, I have hereunto set my hand at San Francisco, California this 90 31st day of July 1916.

JOHN DIERKS.
